CENTRIFUGAL AMALGAMATOR.

1,211,019.

Specification of Letters Patent. Patented Jan. 2, 1917.

Application filed April 19, 1915. Serial No. 22,234.

To all whom it may concern:

Be it known that we, PAUL WEEKS, CHARLES R. MCCOLLOM, and CHARLES O. HASKELL, citizens of the United States, said 5 PAUL WEEKS and CHARLES O. HASKELL residing at Los Angeles, county of Los Angeles and State of California, and said CHARLES R. MCCOLLOM residing at Pasadena, in the county of Los Angeles and 10 State of California, have invented a new and useful Centrifugal Amalgamator, of which the following is a specification.

This invention relates to devices of the character disclosed in the patents of Charles 15 O. Haskell, for metal separating apparatus, dated January 21, 1915, No. 1,148,771, and for amalgamator, dated January 21, 1915, No. 1,148,770.

An object of this invention in common 20 with an object of said former inventions is to separate precious metals from their ores in minimum amount of time and with minimum loss of said precious metals. In this as in said former inventions, the ore is fed 25 into a rotating inverted bowl or drum so that the heavier particles of the ore will tend to be thrown by centrifugal action to the outermost portions of the bowl chamber or passage, the effect of the bowl construction being to somewhat retard the ore particles in their passage to the amalgamating trough which is located at the largest diametral portion of the bowl. In this way the 30 heavier ore particles containing the precious metals will not be thrown radially outwardly in a plane directly into contact with the amalgamating agent as in other centrifugal machines but will more gradually seek the amalgamating agent so that the largest 35 possible amount of the precious metals and the particles containing the same will come into contact with the amalgamating agent to form an amalgam.

An object of this invention in contradistinction to objects of said former inventions 40 is to so construct the device as to retain all of the amalgam in the amalgamating trough, while the machine is running.

Another object is to so construct the device 45 that the ores will be caused to pass through the device without it being necessary to provide a pump for that purpose.

Another object is to so construct the device 50 that a low head will produce all the pressure

that is necessary to cause the ores to pass 55 through the device.

Another object is to so construct the device 60 that it will in itself act as a pump to cause proper flow of the material through the device.

Another object is to facilitate removal of 65 the amalgam from the device.

The accompanying drawings illustrate the invention:

Figure 1 is a side elevation of a centrifugal amalgamator built in accordance with the provisions of this invention. Fig. 2 is a vertical mid section on line indicated by x^2-x^2 , Fig. 1, only a portion of the bracket being shown. Fig. 3 is a plan view on line 70 indicated by x^3-x^3 , Figs. 1 and 2. Fig. 4 is a plan section on line indicated by x^4-x^4 , Figs. 1 and 2, the outer wall of the bowl being partly broken away for clearness of 75 illustration. Fig. 5 is an enlarged detail of the valve, the bushing and portions of the hub and shaft being in vertical mid section. Fig. 6 is an enlarged fragmental plan view of Fig. 2.

There is provided a drum substantially in 80 the form of a hemispherical dome or bowl comprising two sections, an upper section having outer and inner walls 1, 2 spaced apart from one another to form a hemispherical or bowl-shaped passage 3, and a 85 lower section having an outer annular wall 4 and an inner annular wall 5 spaced apart from one another to receive between them the rim 6 of the inner wall 2. The upper section is provided with an inlet 7 communicating with the passage 3 and said inlet is connected, by a hollow shaft in the form of a supply tube 8, to a pulley 9 which may be driven by any suitable power to effect rotation of the bowl. The hollow shaft 8 is 90 concentric with and rotates inside of a stationary tubular member 10 provided at its opposite ends with antifriction bearings 11, 12 for the shaft 8. The tubular member 10 has its upper end inserted in and is supported by a horizontally extending bracket 11' provided with bolt-holes 12' for fastening by bolts, not shown, to a suitable supporting structure, not shown. The pulley 9 is provided with a hollow rectangular hub 13 to 100 form an inlet 14 communicating with the hollow shaft 8.

The upper and lower bowl sections are

hinged together at 15 and the lower section is provided with pins 16 to pivot latch bolts 17 accommodated in slots 18, 19 in the upper and lower sections respectively of the bowl. The upper and lower sections of the bowl may be locked together by a suitable lock 20 located diametrically opposite the hinge 15, the latch bolts 17 being located diametrically opposite one another between the hinge and lock.

The wall 4 slants outwardly and downwardly to form an annular amalgamating trough 21 at the greatest diameter of the bowl communicating with the passage 3, 15 there being an annular outlet 22 between the rim 6 and lower edge of the trough, the bottom of the trough being of greater inside diameter at its lower edge than at its upper edge. The inner wall 5 of the lower section 20 projects inside of the upper section and the rim 6 of the inner wall of the upper section projects below the level of the inner wall 5 of the lower section adjacent the trough 21 and between said trough and inner wall of 25 the lower section. By this construction, when the machine is running, choking of the machine is avoided and the metalliferous material is caused to sweep across the surface 30 of the amalgamating agent in the trough 21 and keep the surface clean and free from refuse, thus maximizing the amalgamating effect. The outlet 22 opens into an annular basin 23, the rim 6 being nearer the outer rim of the basin and spaced apart from the 35 inner rim of the basin so as to form a free annular passage 24 from the basin into the inside expansion chamber 25 of the upper section. The inner rim of the basin joins the wall 5 which extends up above the level 40 of the rim 6 and into the inner chamber 25. The annular wall 5 forms an outlet 26 from the expansion chamber 25 to the exterior of the amalgamator at the bottom thereof. There are provided between the outer and 45 inner walls 1, 2, a series of curved blades or vanes 27 to aid in properly distributing outward and downward the metalliferous material flowing through the passage 3.

The square hub 13 may be provided with 50 suitable valve means and in the instance shown in the drawings said valve means are constructed as follows: The hub 13 is provided interiorly with a rectangular bushing 28 forming at its lower edge a valve seat 29 55 and is provided at its lower part with pins 30 to pivotally mount a pair of oppositely arranged centrifugally-operated flap valves having longer arms 31 and shorter arms 32, the longer arms when closed together in the 60 dotted position shown in Fig. 2 extending aslant upward toward one another with their beveled ends 31 abutting one another to close that portion of the inlet 14 between the valve pivots, and the shorter arms ex- 65 tending aslant downward away from one an-

other with their beveled ends 33 engaging the valve seat 29 so as to close that portion of the inlet between the bushing walls and pivots. The arms 31 may rest against a stop 34 formed by a pin extending transversely of the axis of the bushing. Said valves when open in the position shown in Fig. 2 and in solid lines in Fig. 5 rest against stops 35 and are spaced apart from the bushing walls sufficiently to leave passages 36 between said valves and walls so that the metalliferous material will not become wedged behind the shorter arms of the valves and prevent said valves from closing. Each shorter valve arm 32 is provided with a weight 37 to aid in holding the valves in closed position when the hub is stationary, said weight, however, together with the weight of the arms 31 is overcome by centrifugal force acting on the longer arms when the pulley is rotated by power transmitted thereto as by a belt, not shown, thus opening the valves. The wall 1 is provided at its rim with a bead 38 inwardly overlapping the rim of the wall 4 so as to avoid leakage at the joint between the sections of the bowl, and if desired, packing 39 may be employed to further insure against leakage at said joint.

In practice assuming that the amalgamating agent *a* has been placed in the basin 23, Fig. 2, the pulley 9 will be driven and the metalliferous material to be operated on will be passed in a pulverized, crushed or pulp condition into the inlet 14 and past the valves which have been opened by the action of centrifugal force and thence through the hollow shaft 8 into the upper end of the passage 3. Centrifugal force will throw the material outward and downward and the flow of the material through the passage 3 will be somewhat retarded by reason of the friction between said material and the walls, more especially the outer wall 1 of the upper section, and also between the material and the vanes 27 thus giving time for substantially all of the heavier metallic particles and metal bearing particles to work to the outer periphery of the moving column of material. The material working downward in a hollow column, the heavier metallic particles and metal bearing particles at the periphery of the column come into direct contact with the amalgamating agent in the trough 21 and are amalgamated and retained in said trough while the lighter particles constituting the sludge pass downward through the outlet 22 into the basin 23 and are crowded up through the annular passage 24 over the upper rim of the wall 5 and expand into the inside expansion chamber 25 and thence gravitate downward and out of the machine. After such interval of time as experience and practice show to be sufficient for combining the precious metals and the amalgamating agent to form an amalgam 130

in the trough 21, the lock 20 will be unlocked by the usual key, not shown, and the latch bolts 17 will be thrown out of commission so as to allow the lower section of the bowl to swing downward to a vertical position, thus allowing all of the amalgamated material to flow into and be held by the trough 21. Then the lower section will be swung backward and upward sufficiently far to dump the amalgamated material from the trough 21 into a suitable receptacle, not shown.

It is noted that the centrifugally and gravitationally operated valve is an important feature of the invention for it affords automatic means to shut off the flow of metalliferous material to the machine, if from any cause, as for instance the breaking of the driving belt, the drum ceases to rotate. The valve thus insures against any amalgam contained in the machine from being washed out of the machine if the machine ceases to operate in the prescribed way.

From the foregoing it is clear that by the use of this machine the metal-bearing material is caused to rotate downward in a hollow column, and an amalgamating agent is caused to surround the lower portion of said column to amalgamate the metallic particles at the periphery of the column; also that centrifugal action is set up in the metalliferous material to cause the material to flow outward toward an amalgamating agent, and at the same time the outward flow of the material is retarded so as to facilitate segregation of the heavier particles at the outer portions of the moving material before said material reaches the amalgamating agent.

The process outlined above is not claimed herein and is substantially the same as that carried out by the machines disclosed in the hereinbefore mentioned prior patents in which said process is not claimed, said process being the subject of the copending application of Charles O. Haskell for process of amalgamation, filed April 19, 1915, Serial No. 22,216, said Charles O. Haskell being the sole inventor of said process.

What we claim is:

1. A centrifugal amalgamator comprising a rotatively mounted double walled bowl formed of upper and lower sections free from interlocking overlap so as to allow downward movement of the lower section without other shifting of parts, the lower section having an annular trough and the inner wall of the lower section projecting inside of the upper section and the rim of the inner wall of the upper section projecting below the level of the inner wall of the lower section adjacent the trough, and means to rotate said bowl.

2. A centrifugal amalgamator comprising a rotatively mounted double walled bowl

formed of upper and lower sections free from interlocking overlap so as to allow downward movement of the lower section without other shifting of parts, the lower section having an annular trough and the rim of the inner wall of the upper section projecting below the level of the inner wall of the lower section adjacent the trough, and means to rotate said bowl.

3. A centrifugal amalgamator comprising a bowl formed of upper and lower double walled sections hinged to one another and free from interlocking overlap so as to allow downward movement of the lower section without other shifting of parts, the inner walls being spaced apart radially and overlapping axially, and means to rotate said bowl.

4. A centrifugal amalgamator comprising two separable sections, the upper section having a bowl-shaped passage and an inlet to said passage and having an expansion chamber, and the lower section having an annular basin and an annular wall extending up from the inside rim of the basin into the expansion chamber, the walls of said sections being free from interlocking overlap so as to allow downward movement of the lower section without other shifting of parts, and means to rotate said sections.

5. A centrifugal amalgamator comprising two separable sections free from interlocking overlap so as to allow downward movement of the lower section without other shifting of parts, the upper section having a bowl-shaped passage and an inlet to said passage and having an expansion chamber, and the lower section having an annular trough communicating with said passage and with the expansion chamber and having an outlet for the expansion chamber, the inner wall of the passage extending downward to within a slight distance of the level of the lower margin of the trough, and means to rotate the sections.

6. A centrifugal amalgamator comprising two separable sections free from interlocking overlap so as to allow downward movement of the lower section without other shifting of parts, the upper section having a bowl-shaped passage and an inlet to said passage and having an expansion chamber, and the lower section having an annular trough communicating with said passage and with the expansion chamber and having an outlet for the expansion chamber, the inner wall of the passage extending downward to within a slight distance of the level of the lower margin of the trough and said trough being of greater diameter than the greatest diameter of the upper section and of greater inside diameter at its lower margin than at its upper margin, and means to rotate the sections.

7. A centrifugal amalgamator comprising

- two separable sections free from interlocking overlap so as to allow downward movement of the lower section without other shifting of parts, the upper section having spaced apart walls to form a dome-shaped passage and having an inlet to said passage, and the lower section having an annular wall forming an outlet and having a curved wall forming a basin, said annular wall being spaced apart radially from the rim of the inner wall of the upper section and the inner wall of the upper section terminating over the basin at the greatest diameter of said inner wall, and means to rotate one of said sections away from the other section.
8. A centrifugal amalgamator comprising a rotatively suspended hollow shaft, a double walled bowl section fastened to and suspended from the shaft, the inter wall 20 space communicating with the bore of the shaft, a second bowl section suspended from the first bowl section and free from interlocking overlap therewith and adapted to be opened downward therefrom, and means 25 to rotate said shaft.
9. A centrifugal amalgamator comprising two sections hinged together and free from interlocking overlap so as to allow downward swing of the lower section without 30 other shifting of parts, one of said sections being double walled and provided with an inlet and being provided with an expansion chamber communicating with the inter wall space, and the other section having an 35 outlet from said expansion chamber, a hollow shaft connected to the inlet, a tubular member surrounding said shaft and provided at its opposite ends with bearings for said shaft, and a bracket to suspend the 40 tubular member.
10. A centrifugal amalgamator comprising a double walled bowl-shaped upper section, a lower section having inner and outer annular walls and having an annular basin 45 connecting said annular walls to one another

just below the level of the greater diameter of the inner wall of the upper section, the space between the annular walls of the lower section being greater than the space between the walls of the upper section, a hinge connecting the outer wall of the lower section to the outer wall of the upper section, said walls being free from interlocking overlap so as to allow downward swinging of the lower section without shifting of other parts, and means connected to the upper section to rotate said section.

11. A centrifugal amalgamator comprising a downwardly and outwardly expanding double walled bowl-shaped member, an annular trough at the greater diameter of the outer wall of the bowl-shaped member, the rim of the inner wall of said bowl-shaped member extending almost to the level of the lower margin of the trough and there terminating, and an annular basin just beneath the rim of said inner wall.

12. A centrifugal amalgamator comprising a downwardly and outwardly expanding double walled bowl-shaped member, an annular trough at the greater diameter of the outer wall of the bowl-shaped member, the rim of the inner wall of said bowl-shaped member extending almost to the level of the lower margin of the trough and there terminating, means forming a discharge outlet from the space inside of the bowl, and a hollow shaft to rotatively suspend the bowl-shaped member and having its bore communicating with the inter-wall space.

In testimony whereof, we have hereunto set our hands at Los Angeles, California, this 9th day of April, 1915.

PAUL WEEKS.

CHARLES R. McCOLLOM.
